United States Patent Office

Des. 232,396

Patented Aug. 20, 1974

232,396

WET SUIT

Robert Maxwell Seddon, Knaresborough, England, assignor to Unitex Limited, Knaresborough, England

Filed May 15, 1972, Ser. No. 253,689

Claims priority, application Great Britain Mar. 23, 1972

Term of patent 14 years

Int. Cl. D2—02

U.S. Cl. D2—40

The figure is a front perspective view of a wet suit showing my new design, the rear of the wet suit being plain.

I claim:

The ornamental design for a wet suit, substantially as shown and described.
